INTERCHANGEABLE UTILITY TABLE

Lauretta J. Usher, Chicago, Ill.

Application April 27, 1950, Serial No. 158,460

5 Claims. (Cl. 312—194)

1

This invention relates to interchangeable utility tables and more particularly to a multi-purpose table structure which in one position of adjustment has the utility and appearance of a flat top table or desk, and in another position of adjustment serves the purposes of an inclined table particularly suited for writing, drawing and drafting purposes.

In accordance with this invention, an interchangeable utility table is provided which comprises a pair of spaced end sections and an interchangeable and tiltable section mounted between the end sections and adjustable to provide either a flat top table or desk or an inclined working surface. Each end section may be made in any desired width or depth, equipped with one or more drawers, and presenting a fixed table top panel extending in a horizontal plane. The end sections are connected together in spaced relationship by a rear frame member and a front frame member. The tilting section comprises a drawer or tray which is hinged to the front frame member, the tray being normally closed by an intermediate table top panel which is hinged to the rear wall of the tray. The intermediate tilting section is hinged supported at the front thereof by the front frame member, and the rear thereof is designed to be supported by the rear frame member when the intermediate section is in horizontal position, in which position the intermediate table top panel will lie in a horizontal plane substantially flush with the adjacent fixed table top panels of the end sections so that a substantially flat and continuous table top surface is provided which extends over the entire top area of the table.

Adjustable supporting devices are provided to support the intermediate section in inclined position so that the intermediate table top panel presents a conveniently inclined work surface for writing, drawing or drafting. The adjustable supporting devices have latch dogs associated therewith for automatically locking the intermediate section in the desired inclined position when the rear of the tilting section is raised to the required degree by exerting a lifting force on rear edge of the intermediate table top panel. The intermediate section may be released from its inclined position by exerting an incremental forward pull on the rear edge of the intermediate top wall panel sufficient to effect release of the latch dog which supports the intermediate section in tilted position, thereby permitting the intermediate section to be dropped down to horizontal table forming position. Access to the tray form-

2

ing a part of the intermediate section may be had by lifting the front edge of the intermediate table top panel upwardly, which gives unobstructed access to the entire interior area of the intermediate tray. The intermediate section is so constructed that the intermediate table top panel when swung open is retained in vertical extended open position so that both hands may be used to select and handle papers and materials within the tray without the necessity of holding the intermediate top wall panel in open position.

This improved interchangeable utility table may be constructed to a size and height to serve as a child's utility table. When the intermediate section is adjusted to horizontal position, the flat and continuous table top area extends over the entire top area of the table so that the table can then be used for eating and game purposes with ample drawers and compartments to contain children's game, toy and writing paraphernalia. When the intermediate section is adjusted to inclined position, the inclined intermediate table top panel provides a convenient writing or drawing surface with the necessary accessories available in the tray forming a part of the tilting section and the drawers forming a part of the end sections. This improved utility table is so constructed to avoid any danger that the child may become injured in its use.

This improved utility table may also be shaped and designed within the purview of this invention to provide a bed table for invalids, in which case the table would be made light in weight and of convenient height with the end sections spaced to straddle the lower body or legs when extended under the intermediate section, and with the end sections resting on the side edges of the mattress or the side frames of the bed. When the intermediate section is adjusted to horizontal position, a flat and continuous table top is presented for eating and game purposes, and when adjusted to inclined position it is conveniently adapted for writing, drawing and drafting purposes with all the necessary materials and paraphernalia available in the intermediate tray and in the drawers of the end sections.

This improved utility table may also be designed and adapted within the purview of this invention for the convenient use of artists and draftsmen who prefer to perform their drawing or drafting work on an inclined surface, with ample and conveniently located drawers and tray space to contain the writing and drawing papers and materials, and with the top wall panels of

the end sections providing flat surfaces on which to place additional papers and materials used in their work. When the intermediate section is adjusted to horizontal position, the flat table surface thus provided is particularly convenient when writing or dictating letters and memoranda.

Other objects and advantages of this invention will become apparent as the disclosure proceeds.

While certain novel features of this invention have been disclosed and are pointed out in the annexed claims, it will be understood that various omissions, substitutions and changes may be made by those skilled in the art without departing from the spirit of this invention.

Fig. 1 is a perspective view of my improved interchangeable utility table showing the intermediate tilting section thereof in closed position to provide a flat and continuous table top.

Fig. 2 is a longitudinal cross-sectional view of the utility table as the same would appear when viewed along line 2—2 of Fig. 1.

Fig. 3 is a perspective view of the utility table showing the intermediate section thereof in fixed tilted position at a convenient angle to provide an inclined writing or drawing board.

Fig. 4 is a perspective view illustrating the supporting structure for the table as the same would appear when the sliding drawers and the table top panels are removed from the end sections and the intermediate tilting section is removed from the table structure.

Fig. 5 is a perspective view of the utility table showing the intermediate table top panel swung into full open position to provide ready access to the intermediate storage tray.

Fig. 6 is a transverse cross-sectional view taken through one of the end sections of the utility table as the same would appear when viewed along line 6—6 of Fig. 2.

Fig. 7 is a transverse cross-sectional view of the utility table showing the intermediate section supported in tilted position as the same would appear when viewed along line 7—7 of Fig. 3.

Fig. 8 is another transverse cross-sectional view through the utility table as the same would appear when the intermediate table top panel has been swung into full open position and viewed along line 8—8 of Fig. 5.

Fig. 9 is a fragmentary detail of the lower end of one of the bracket arms showing the associated latching dog as it would appear when about to be disengaged from the fixed stud which supports the intermediate section in fixed tilted position.

Fig. 10 is a fragmentary cross-sectional view of the utility table as the same would appear when viewed along line 10—10 of Fig. 1, this view particularly illustrating the manner in which the rear edge of the intermediate table top panel is supported in closed position by the rear frame member of the table; and

Fig. 11 is another fragmentary cross-sectional view taken along line 11—11 of Fig. 1 showing the intermediate table top panel in process of being swung into open position.

Similar reference characters refer to similar parts throughout the several views of the drawings and the specification.

Referring to the drawings, this improved interchangeable utility table generally comprises a pair of spaced end sections 1 and an intermediate section 25 tiltably mounted therebetween. Each end section 1 comprises an outer leg forming panel 2 and an inner leg forming panel 3 in parallel arrangement as shown more particularly in

Fig. 4. The outer and inner leg forming panels 2 and 3 may be connected by a front facing panel 4 extending from the bottom of the leg forming panels upwardly for only a fractional part of the height thereof to leave room for one or more sliding drawers thereabove. The rear vertical edges 5 of the inner and outer leg forming panels may have a rear facing panel 5 secured to and extending therebetween for the full height thereof.

The end sections 1 of the table are connected by a horizontally extending rear frame member 6 whose ends 7 may be secured to the adjacent rear edge faces of the outer leg forming panels 2 in a manner so that the top edge 6' of the rear frame member 6 is substantially flush with the top edge 8 of the outer and inner leg forming panels 2 and 3 of the end section, as shown more particularly in Fig. 4. The rear vertical edge of the inner leg forming panel 3 may be provided with a notch 9 to neatly receive the rear frame member as shown in Fig. 4. The rear frame member 6 may be secured to the inner leg forming panels 3 as by screws 8' or the like as shown in Fig. 7. The end sections 1 are also connected by a front frame member 9 whose ends are connected as by screws or dowel pins 9' to the adjacent faces of the inner leg forming panels 3. It will be noted by referring to Figs. 4, 7 and 8 that the front edge of the front frame member 9 may be substantially flush with the front vertical edges of the inner leg panels 3, with the top face of the front frame member 9 extending horizontally and positioned a distance below the top horizontal edges of the inner leg forming panels 3. The upper horizontal 20 face of the front frame member 9 may be provided with spaced notches 10 to receive the hinges 11 which pivotally connect the intermediate tilting section 25 thereto.

Each end section 1 may be provided with a pair 40 of drawer supporting side strips 11 and a front strip 12 secured to the inner faces of the outer and inner leg forming panels 2 and 3, said strips being designed and arranged to support a sliding drawer. The right hand end section as shown in Figs. 1, 3, 4 and 5 contains a relatively deep 45 drawer 15 slidably supported on the drawer guide strips 11 and 12 associated with the left hand end section of the table support a relatively shallow drawer 16. Thus an additional set of side strips 13 and a front strip 14 as shown in Figs. 1, 2, 4 and 5 may be associated with the left hand end section to support a second and upper sliding drawer 17 of 50 relatively shallow depth. It will be appreciated that any selection of sliding drawers of varied 55 depth may be mounted in the table end sections 1 and 2 as may be desired. The front panel of each of the drawers 15, 16 and 17 may be provided with a handle forming pocket 18 to provide a convenient finger grip by means of which the 60 drawer may be manipulated. Likewise, the outer leg forming panel 2 of each end section may be provided with a handle forming pocket 19 as shown in Figs. 1, 3, 4 and 5 by means of which the utility table as a whole may be conveniently 65 lifted and carried.

Each of the end sections has a table top forming panel 20 which is suitably secured to the upper horizontal edges of the outer and inner leg forming panels 2 and 3 thereof to provide a fixed table surface. The front edge 21 of each 70 table top panel 20 may overhang or be made substantially flush with the front vertical edges of the leg forming panels 2 and 3, the rear edge 22 thereof may overhang or be made substantially 75

flush with the outside face of the rear panel 5, the outer side edge 23 thereof may overhang or be made substantially flush with the outside face of the outer leg forming panel 2, and the inner side edge 24 thereof may also overhang or be made substantially flush with the outer face of the inner leg forming panel 3.

The intermediate tilting section 25 of this utility table generally comprises a tilting storage drawer or tray 26 which is designed to snugly nest between the inner leg panels 3 of the end sections 1. The tilting tray 26 is formed by sturdy side wall members 27 whose ends are secured to a front wall tray panel 28 and a rear wall member 29 which support a bottom panel 30. The tray 26 is hingedly connected to the front frame member by the spaced strap hinges 31 secured to the lower edge of the front wall tray panel 28, the hinges 31 being inset into the hinge notches 10 in the front frame member 9 and secured thereto in a manner to render the hinges substantially invisible when the table is viewed from the front thereof.

The intermediate drawer or tray 26 is closed by an intermediate table top panel 32 which is complementary to the table top panels 20 associated with the end sections 1. Thus when the intermediate tilting section 32 is at rest in its normal horizontal position, a substantially smooth and flat table surface for the entire table is provided, with a front edge 33 and the rear edge 34 of the table panel 32 substantially in alignment with the respective front and rear edges 21 and 22 of the end table top panels 20, and with the side edges 35 of the intermediate table top panel 32 substantially flush with the adjacent inner side edges 24 of the end table top panels 20. Any possible finger pinching injury to the user is avoided by making each side edge 35 of the top panel flush with the outside face of the adjacent side wall member 27 of the tray 26.

As shown in Figs. 7 and 10, a pair of strap hinges 36 hingedly connect the intermediate table top panel 32 to the rear wall member 29 of the tilting tray 26. By referring to Figs. 8, 10 and 11, it will be noted that the rear wall member 29 of the tray 26 is designed to swing within the rear frame member 6 with the overhanging rear portion of the intermediate table top panel 32 designed to rest on the upper edge 6' of the rear frame member 6 so that the rear portion of the tray 26 is suspended from the intermediate table top panel. A bumper strip 37 formed of resilient rubber or the like is inset into the under face of the intermediate table top panel 32 and is arranged to resiliently bear against the upper edge 6' of the rear frame member 6 when the intermediate table top panel 32 is in its horizontal position as shown in Fig. 10.

A finger grip cutout 38 is formed in the front edge 33 of the intermediate table top panel 32 by means of which the panel 32 may be grasped and swung upwardly as shown in Fig. 11 to its full open position as shown in Figs. 5 and 8. When swinging the table top panel 32 to open position, it will be noted by referring to Fig. 11 that the rear lower corner 34' thereof slides over the top edge 6' of the rear frame member 6, the rear edge of the tray 26 then being raised a corresponding amount. When the table top panel 32 has been swung into full open position as shown in Figs. 5 and 8, the rear edge 34 of the table top panel 32 will seat flatly against the top edge 6' of the rear frame member 6 as shown in

Fig. 8, with the bumper strip 37 in contact with the rear wall member 29 of the tilting tray 26. As thus positioned, the intermediate table top panel 32 will remain in vertical extended position as shown in Fig. 5 without further support, permitting convenient access to papers and material contained within the tray 26.

The rear edge 34 of the intermediate table top panel 32 is also provided with a suitable finger grip cutout 39 by means of which the same may be grasped by a person sitting or standing in front of the table, and thereby lift the rear of the tilting section 25 upwardly to the desired inclined or tilted position as indicated in Figs. 3 and 7.

Supporting devices 40 are provided for readily retaining the intermediate section in the desired tilted position. These supporting devices 40 may comprise a pair of strut arms 41, each of which is pivotally connected at the upper end thereof by a sturdy pin 42 projecting from an angle bracket 43 secured to the lower edge of the adjacent side frame member 27 of the tray as indicated in Figs. 2, 7 and 8. Each strut arm 41 is provided with an elongated closed end slot 44 extending substantially the full length thereof. A stud pin 45 projects from a securing plate 46 which is secured as by screws 47 to the inside face of the adjacent inner leg panel 3 of each end section 1. Each stud supporting securing plate 46 is located sufficiently below the upper horizontal edge of the inner leg panel 3 to permit the tray 26 to assume the intended horizontal position. The stud 45 extends through the elongated slot 44 in the strut arm 41 and may be provided with a head portion 48 to retain the strut arm in sliding engagement with the stud pin 45.

Each strut arm 41 has a latch dog 50 hingedly connected thereto as by a hinge rivet 51 as shown in Figs. 7, 8 and 9. The latch dog 50 has a front cam face 52 which normally overhangs the elongated slot 44 and against which the fixed stud pin 45 may cam to swing the latch dog upwardly when the tilting section 25 is raised to approximately its intended tilted position. A further incremental raising movement of the tilting section 25 will cause the tip portion 53 of the dog to ride over the stud pin 45, permitting the latch dog to swing downwardly so that its concave saddle portion 54 will seat over the stud pin 45 and thus rigidly retain the tilting section 25 in fixed tilting position.

When the tilting section 25 is to be dropped back into horizontal position, the rear edge of the tilting section is further raised an incremental amount so that the leg 55 of the dog as shown in Fig. 9 is no longer supported by the stud pin 45, whereupon the latch dog is free to swing downwardly with the stud pin 45 located to the rear of the rear cam face 56 of the dog. The tilting section 25 can then be lowered, with the stud pin initially camming against the rear cam edge 56 of the latch dog so as to swing the latch dog forwardly as the strut arm moves downwardly.

The lower end of each strut arm 41 is encased in a resilient bumper 57 which may be formed of rubber molded around the lower end of the strut arm. In finally releasing the tilting section 25 from the supporting influence of the stud pin 45, the incremental forward pull exerted on the rear edge of the intermediate table top panel 32 is sufficient to effect compression of the resilient bumper 57 by the pressure exerted by the

hinge stud pin 45 thereagainst before the dog 50 is free to swing downwardly clear of the stud pin 56. The resilient bumper 51 thus serves to indicate when the latching dog 50 has been withdrawn from the supporting influence of the stud pin 45.

From the above disclosure, it is apparent that interchangeable utility tables may be constructed in accordance with this invention in various sizes and forms to serve as a child's play table, a draftsman or artist's work bench or table or as a general utility table for hospital beds. The table may be constructed to any height, length and width dimensions and equipped with any desired number of drawers, trays or compartments to most conveniently serve the purposes for which it is intended. Matching edging strips 63, 64 and 62 may be secured round the edges of the top wall panels 28 of the end sections 1 and the top wall panel 32 of the intermediate tilting section 25 to prevent papers and other materials from sliding off. Utility tables may be constructed in accordance with this invention from wood, metal or plastics of selected weight and strength, may be artistically designed in various shapes and colors and can be manufactured at modest cost.

While certain novel features of this invention have been disclosed and are pointed out in the annexed claims, it will be understood that various omissions, substitutions and changes may be made by those skilled in the art without departing from the spirit of this invention.

What is claimed is:

1. An interchangeable utility table including in combination, a pair of end sections each having a horizontally extending table top panel, a rear frame member and a front frame member connecting said end sections in fixed spaced relationship, an intermediate section positioned between said end sections and presenting a containing tray having a table top panel swingably hinged to the rear edge of said tray and providing a closure cover therefor, and means for hingedly connecting said intermediate section to said front frame member to permit swinging movement of said intermediate section to and from inclined position, said intermediate table top panel having a rear extension adapted to rest on said rear frame member to support the intermediate section in horizontal position with the intermediate table top panel thereof substantially flush with the table top panels of said end sections.

2. An interchangeable utility table including a pair of end sections each having a horizontally extending table top panel, a rear frame member and a front frame member connecting said end sections in fixed spaced relationship, an intermediate section positioned between said end sections and presenting a containing tray having a table top panel swingably hinged to the rear edge of said tray and providing a closure cover therefor, means for hingedly connecting said intermediate section to said front frame member to permit swinging movement of said intermediate section to and from inclined position, said intermediate table top panel having a rear extension adapted to rest on said rear frame member to support the intermediate section in horizontal position with the intermediate table top panel thereof substantially flush with the table top panels of said end sections, and a resilient bumper strip secured to the underface of said rear extension and designed to rest on said

5 open position.

3. An interchangeable utility table including in combination, a pair of end sections each presenting an inner leg panel and an outer leg panel connected by a horizontally extending table top panel and having one or more sliding drawers mounted between said inner and outer leg panels, a rear frame member and a front frame member connecting said end sections in fixed spaced relationship, an intermediate section positioned between said end sections and presenting a containing tray having a table top panel swingably hinged to the rear edge of said tray and providing a closure cover therefor, means for hingedly connecting said intermediate section to said front frame member to permit swinging movement of said intermediate section to and from inclined position, said intermediate table top panel having a rear extension adapted to rest on said rear frame member to support the intermediate section in horizontal position with the intermediate table top panel thereof substantially flush with the table top panels of said end sections, and adjustable devices operably connected to said intermediate section and said end sections for adjustably supporting said intermediate section in inclined position.

4. An interchangeable utility table including in combination, a pair of end sections each having inner and outer side panels, a back panel, and a fixed table top panel defining a containing compartment accessible from the front thereof, a rear frame member and a front frame member connecting said end sections in fixed spaced relationship, an intermediate section positioned between said end sections and presenting a containing tray having a bottom wall panel, enclosing front, rear and side wall panels and a table top panel swingably hinged to the upper edge of the rear wall panel and providing a closure cover therefor, said front frame member having an upper surface extending substantially parallel to but substantially below the plane of the top panels of said end sections and providing a support for the front end of said intermediate section, means associated with said rear frame member and intermediate section for supporting the rear end of said intermediate section in horizontal position with the table top panel thereof substantially flush with the table top panels of said end sections, means for hingedly connecting the lower edge of the tray front panel to said front frame member whereby said intermediate section may be swung to and from selected horizontal and inclined positions, and spaced bracket devices operatively connected to said intermediate section and end sections for adjustably supporting said intermediate section in inclined position, said bracket devices having locking elements associated therewith automatically operative by initial incremental swinging movement of said intermediate section to selectively lock and unlock said intermediate section in inclined position.

5. An interchangeable utility table including in combination, a pair of end sections each having inner and outer side panels, a back panel, a fixed table top panel and one or more forwardly slideable drawers mounted therein, a rear frame member and a front frame member connecting said end sections in fixed spaced relationship,

an intermediate section positioned between said end sections and presenting a containing tray having a bottom wall panel, enclosing front, rear and side wall panels and a table top panel swingably hinged to the upper edge of the rear wall panel of the tray and providing a closure cover therefor, said front frame member having an upper surface extending substantially parallel to but substantially below the plane of the top panels of said end sections and providing a support for the front end of said intermediate section, means associated with said rear frame member and intermediate section for supporting the rear end of said intermediate section in horizontal position with the table top panel thereof substantially flush with the table top panel of said end sections, means for hingedly connecting the lower edge of the tray front panel to said front frame member whereby said intermediate section may be swung to and from selected horizontal and inclined positions, and spaced bracket devices operatively connected to

said intermediate section and end sections for adjustably supporting said intermediate section in inclined position, said bracket devices having locking elements associated therewith automatically operative by initial incremental swinging movement of said intermediate section to selectively lock and unlock said intermediate section in inclined position.
